G. M. GALE

LOOSE LEAF BINDER

Filed Aug. 31, 1926

UNITED STATES PATENT OFFICE.

GORDON M. GALE, OF MAYWOOD, CALIFORNIA.

LOOSE-LEAF BINDER.

Application filed August 31, 1926. Serial No. 132,826.

This invention relates to loose leaf binders and the general object of the invention is to provide improved means whereby the loose leaves may be engaged with the binder and a further object is to so form the binder that it will be particularly strong and yet so flexible that the covers may be bent back upon or underneath each other.

My invention is illustrated in the accompanying drawings wherein:

Figure 1 is a perspective view of a loose leaf binder constructed in accordance with my invention, the figure showing in full lines the covers folded over upon each other, and in dotted lines the covers open;

Fig. 2 is a fragmentary transverse section through the binder;

Fig. 3 is a fragmentary edge elevation;

Fig. 4 is a fragmentary perspective view of one of the covers;

Fig. 5 is a section showing the means of attaching the strip 15.

Referring to these drawings it will be seen that the binder consists of the two cover sections 10 and 11 which may be made of pasteboard or any other suitable material. The inner edges of these cover sections are spaced from each other but connected to each other by the outer and inner layers of buckram or like textile fabric designated 12.

Disposed between the inner edges 13 of the covers 10 and 11 and between the outer and inner edges of the buckram 12 is a strip 14 of cardboard or any like material constituting the back of the book and also a flexible connection between the covers of the book. Disposed on the inside of the

section 11 but covered by the buckram 12, is a metallic strip 15 which is attached to the cover section 11 at a plurality of points as, for instance, by split rivets or equivalent devices 16.

Carried by the strip 15 are the pliable wire clips 17 designed to support the loose leaves of the book. The inner end of these wires 17 is enlarged to form a rivet 18 and preferably the strip 15 is notched at 19 to receive the bill of the hook-shaped wire 17 when the latter is closed to a turned position. These pliable wires may be opened to permit their insertion through the perforations in the leaves of the book and may be then closed to a position where the bill is engaged within the slot or notch 19. This construction is adapted to be used for any and all loose leaf book bindings and one of the particular features of the invention is that the top section may be folded clear back and under the bottom section, as shown in Figure 1. I do not wish to be limited to the particular shape or character of the book shown as the invention may be applied to many different shapes.

I claim:

A loose leaf binder including a cover section, a metallic strip attached to one face of said cover section, and pliable metallic clips having their inner ends overturned upon the inner face of the metallic strip, the metallic strip at its edge having open notches for the ends of said pliable clips.

In testimony whereof I hereunto affix my signature.

GORDON M. GALE.
